Robert J. McVicker,
INVENTOR.

WITNESS: Ely Feinle

BY Victor J. Evans,
ATTORNEY.

UNITED STATES PATENT OFFICE.

ROBERT J. McVICKER, OF NEW YORK, N. Y.

FOUNTAIN PEN.

Application filed August 20, 1921. Serial No. 493,808.

To all whom it may concern:

Be it known that I, ROBERT J. McVICKER, a citizen of the United States, residing at New York city, in the county of New York 5 and State of New York, have invented new and useful Improvements in Fountain Pens, of which the following is a specification.

This invention relates to fountain pens and the principal object is to produce a device of this nature in which the cap normally used to protect the pen point shall be so constructed that it may be utilized as a pump for filling the barrel of the pen.

Another object is to construct a device of this nature which shall be simple of construction, easy to assemble, cheap to manufacture, and highly efficient for the purpose described.

With these and other objects in view, the invention resides in certain novel construction and combination and arrangement of parts, the essential features of which are hereinafter fully described, are particularly pointed out in the appended claims, and are 20 illustrated in the accompanying drawing, in which:—

Figure 1 is an enlarged longitudinal sectional view of my improved fountain pen.

Figure 2 is a fragmentary detached view 30 of the barrel and valve.

Figure 3 is a similar view of the outer cap sleeve.

Figure 4 is a similar view of the inner cap sleeve.

Like characters of reference refer to like parts in all views.

Referring to the drawing in detail, 10 represents the barrel of a fountain pen provided near opposite ends with threads 11 and 12. The barrel 10 is also provided with a reduced upper end plug 13 having a way 14 formed therein, the inner mouth of which is protected by a gauze float basket 15 in which is suspended a cork or other float 16. A cap 17 screws down on the portion 13 and has threaded into its end a valve 18 provided with a by-pass 19 and tapered at its inner end so that it may be screwed into way 14 to completely stop the same.

The cap comprises inner and outer sleeves 20 and 21, respectively. The sleeve 20 is provided with internal threads 22 at its open end, which match threads 11 and 12. The other end of member 20 is enlarged to form a shoulder 23, and internally threaded at

24 to receive a plug 25 and cooperative cap 26 between which is a valve member 27. Air passage or ducts 28 and 29 are formed in members 25 and 26.

The outer sleeve 21 is provided with an internal shoulder 30 co-acting with shoulder 23 to limit relative movement of the sleeves 20 and 21. The upper end of sleeve 21 is provided with plug cap and valve body 31, 32 and 33 having ways 34 and 35 all similar to those for sleeve 20.

In assembling, the device, the sleeve 20 and its contained parts are first assembled, and then this sleeve complete is pushed down in sleeve 21, and the parts 31, 32 and 33 are put in place. In order to prevent turning 70 of sleeve 21 on sleeve 20 when screwing the cap on or off either end of the barrel, dowel pins 36 on plug 31 seat themselves in holes formed in member 26 when members 31 and 26 are in juxtaposition.

In operation, when the pen needs filling, first screw out member 18 far enough to open passage 14. Then screw cap 20—21 on the threads 12. Dip the pen point in ink and move 21 up relatively to 20 which will draw 80 a charge of ink into the barrel 10. If desired the relative capacities of the parts may be made such that any desired number of reciprocations of member 21 may be required to fill the barrel. When the barrel is full, float 16 will stop passage 14 and no more ink can be sucked up.

While I have described what I deem to be the most desirable embodiment of my invention, it is obvious that many of the details may 90 be varied without in any way departing from the spirit of my invention, and I therefore do not limit myself to the exact details of construction herein set forth nor to anything less than the whole of my invention limited 95 only by the appended claims.

What is claimed as new is:—

1. A fountain pen comprising a barrel a valve at one end of said barrel, a cap formed of two co-operating sleeves adapted to be threadedly engaged with either end of said barrel, and valves carried by said cap and operable for effecting suction at said first mentioned valve, as and for the purpose set forth.

2. A fountain pen comprising a barrel, a valve at one end of said barrel, a cap formed of two co-operating sleeves, and means whereby movement of one of said sleeves

with relation to the other will effect suction at said valve, as and for the purpose set forth.

3. A fountain pen comprising a barrel, a cap formed of two co-operating sleeves, and co-operative valves in said barrel and sleeves.

4. A fountain pen comprising a barrel, a

cap formed of two co-operating sleeves including means for pumping a charge of ink into said barrel, and means in said barrel for stopping further pumping of ink when said barrel is fully charged. 10

In testimony whereof I have affixed my signature.

ROBERT J. McVICKER.
